UNITED STATES PATENT OFFICE.

ANTON SCHROEDER, OF ST. PAUL, MINNESOTA.

SASH-BOWER.

933,587.

Specification of Letters Patent. Patented Sept. 7, 1909.

Application filed November 30, 1908. Serial No. 465,038.

To all whom it may concern:

Be it known that I, ANTON SCHROEDER, a citizen of the United States, residing at St. Paul, in the county of Ramsey and State of Minnesota, have invented certain new and useful Improvements in Sash-Bowers, of which the following is a specification.

My invention relates to improvements in sash bowers and fasteners, its object being 10 to provide improved means for bowing out swinging window sash and shutters, and fastening them in either open or closed position, so that the sash may be easily manipulated and firmly held against displacement.

15 To this end the invention consists in the construction, combination and arrangement of parts hereinafter described and claimed.

In the accompanying drawings forming part of this specification, Figure 1 is a perspective view of a fragment of a window frame and swinging sash fitted with the improved sash bower, with the sash held in outswung position; Fig. 2 is a perspective view upon a larger scale of the slotted bracket and a fragment of the stay bar, with 20 the bar in position to be removed; Fig. 3 is a detail showing the slotted bracket and stay bar in locked engagement, the bracket in front elevation and the stay bar in section 25 on line $x-x$ of Fig. 2; Fig. 4 is a side view of a fragment of a window casing and sash showing the sash closed and the stay bar fastened, and Fig. 5 is a front view of the 30 stay bar and slotted bracket with a fragment 35 of the window stop, showing the stay bar fastened down.

In the drawings A represents a window frame or casing having a vertical strip or stop 2, and B represents a window sash 40 hinged to the upper part of the window frame (hinging not shown) so as to swing in a vertical plane.

Upon the inner face of the window sash is an angle bracket 3, to the outwardly projected lug 4 of which is pivoted a vertically swinging stay bar C. At its free end the stay bar has sliding support within the angular slotted projection of an angle bracket D secured upon the inner side of the stop 2. 45 The slotted projection of the angle bracket comprises two laterally projecting upper and lower arms 5 and 6, having end portions extending downwardly and upwardly, respectively, toward each other a sufficient 50 distance to embrace and retain the stay bar which works within the slot or passage be-

tween the arms. The bracket is formed with an outwardly extending tongue or plate 13 at the base of the arms which extends to the outer edge of the stop 2 and forms a guide for the proper placing of the bracket.

The stay bar is wider than the space between the inturned ends of the arms, so that, once within the arms, it cannot be 65 drawn out sidewise except where the bar is notched to reduce its width sufficiently to permit withdrawal. To enable it to be withdrawn when desired the bar is formed at a 70 convenient place along its length with a notch 7 in its upper edge, as illustrated in Fig. 2, the lower edge of the bar being left unnotched so that it will slide smoothly over the lower arm of the slotted bracket when the window is swung out or pulled in. In 75 order to guard against accidental removal of the bar when the sash is shaken by wind, the notch is made with vertical sides, as shown in the drawings, and of a width just sufficient to permit the upper arm to pass 80 through it.

In order that the bar, when the sash is bowed out, may interlock automatically with the slotted bracket D, it is formed at its outer end with a notch 8 in its lower edge adapted 85 to drop over the lower arm 6 of the bracket, as illustrated in Fig. 3. To prevent the bar from being withdrawn sidewise from between the arms 5 and 6 at the notch 8, it is formed above the notch with a shoulder 9 90 so that the portion of the bar above the notch will be wider than the space between the ends of the arms, as shown in Fig. 3. At its extreme free end the bar is formed with a laterally extending finger piece 10 which 95 forms one side of the terminal notch 8, thus enabling the bar to be extended its entire length.

In practice the stay bar is brought to a position where the notch 7 registers with the 100 ends of the guide arms, and pressed in between them. It is then free to slide within the arms. To open the sash the bar is run out through the slot or opening formed by these arms until the notch 8 drops over the 105 lower guide arm 6, when the sash will be held fast in extended position, as shown in Fig. 1. To close the sash the stay bar is lifted out of engagement with the lower arm and permitted to slide back through the 110 slotted bracket until the sash lodges against the window stop 2. The lug 4 of the angle

bracket 3 will enter and pass through the slotted bracket D and permit the stay bar to swing down upon its pivot into the position shown in Figs. 4 and 5. In this position the 5 sash will be held closed and cannot be swung out until the stay bar has been lifted. I further provide positive means for fastening the stay bar in downturned position, in order that it may not become displaced when the window 10 is shaken by the wind. For this purpose the stay bar is formed near its free end with a slotted opening 11 which fits over a pin 12 driven into the window stop in position to enter the slotted opening, as illustrated in 15 Figs. 4 and 5. As shown in dotted lines in Fig. 5, the stay bar has to be sprung in side- 20 wise in order that it may be fitted over the pin. Once over the pin it will be firmly locked and incapable of dislodgment by the wind or the shaking of the window.

In order to permit the sash to be drawn snugly against the outer face of the window strip 2, the slotted bracket D must be positioned upon the window strip so that the angular or lateral arms 5 and 6 will stand far enough back from the outer face of the strip to receive and accommodate between them and the plane of the face of the strip the base portion of the angle bracket 3 upon the 25 sash. The adjustment of the bracket in this position is a matter of some nicety, and, if done by the eye alone, is apt to result in imperfect closing of the sash or interference with the swinging of the stay bar. I have 30 therefore provided, as a positive and accurate guide for the adjustment of the bracket, a blunt ended tongue 13 extending outwardly from the base of the bracket (that is, the portion at the base of the arms) and 35 projecting beyond the plane of the arms a distance equal to the space desired between the arms and the outer face of the window strip. Thus, when the outer end of the tongue, which is made parallel with the arms, 40 is placed flush with the outer face of the window strip, the slotted bracket will stand in proper position, as shown in Fig. 2 of the drawings.

I claim as my invention:

50 1. The combination, with a window frame and swinging sash, of a slotted angle bracket upon the inner side of the frame, said bracket being formed with spaced upper and lower arms extending laterally into the window 55 opening, a forwardly projecting lug upon the sash, and a stay bar pivoted to the lug so as to swing in a vertical plane, the stay bar

having sliding support between the arms of the slotted bracket and the lug being constructed to enter and pass through the space 60 between the arms of the bracket, so as to permit the stay bar to swing down upon the inside of the bracket.

2. The combination, with a window frame having a window strip upon its inner side, 65 of a slotted angle bracket secured upon the inner side of the strip with its slotted angular portion extending laterally into the window opening and having at the base of the angular portion a tongue projecting outwardly beyond the outer face thereof, a swinging sash, a forwardly projecting lug upon the sash, and a stay bar pivotally connected with the lug so as to swing in a vertical plane and having sliding support in 75 the slotted bracket.

3. The combination, with a window frame having a window strip upon its inner side, 80 of a slotted angle bracket secured upon the inner side of the strip, said bracket being formed with spaced upper and lower arms extending laterally into the window opening and having at the base a tongue projecting outwardly beyond the outer face of the arms, 85 a swinging sash, an angle bracket secured upon the face of the sash and having a forwardly projecting lug, and a stay bar pivotally connected with the lug so as to swing in a vertical plane, the stay bar having sliding support between the arms of the slotted 90 bracket and being formed with a removal notch and a locking notch.

4. The combination, with a window frame having a window strip upon its inner side, 95 of a slotted angle bracket secured upon the inner side of the strip, said bracket being formed with spaced upper and lower arms extending laterally into the window opening, and having at the base of the arms a tongue projecting outwardly beyond the outer faces 100 thereof, the outer face of the tongue being flush with the outer face of the window strip, a swinging sash, an angle bracket secured upon the face of the sash, and a stay bar pivotally connected with the angular projection of said bracket and having sliding support in the slotted bracket.

In testimony whereof I affix my signature in presence of two witnesses.

ANTON SCHROEDER.
